UNITED STATES PATENT OFFICE.

JOHN G. HODGSON, OF MAYWOOD, ILLINOIS, ASSIGNOR TO AUTOMATIC VACUUM CANNING COMPANY, OF CHICAGO, ILLINOIS, A CORPORATION OF ILLINOIS.

AUTOMATIC DOUBLE-SEAMING MACHINE.

SPECIFICATION forming part of Letters Patent No. 727,630, dated May 12, 1903.

Application filed August 21, 1902. Serial No. 120,441. (No model.)

To all whom it may concern:

Be it known that I, JOHN G. HODGSON, a citizen of the United States, residing in Maywood, in the county of Cook and State of Illinois, have invented a new and useful Improvement in Automatic Double-Seaming Machines, of which the following is a specification.

My invention relates to machines for automatically seaming covers on cans or vessels.

The object of my invention is to provide an automatic machine of a simple, efficient, and durable construction by means of which the heads of cans may be rapidly, cheaply, and properly double-seamed upon sheet-metal cans or vessels.

My invention consists in the means I employ to accomplish this result—that is to say, it consists in the combination with a continuously-moving carrier having a plurality or series of chucks thereon for receiving and clamping the cans or vessels and a plurality of sets of double-seaming rollers or tools mounted on the carrier, means for automatically reciprocating one of the chuck-disks as the carrier travels, means for operating the seaming rollers or tools, and means for imparting a rotary motion to the seaming rollers or tools in respect to the cans or vessels.

It also consists in combination, with a movable carrier having a plurality of chuck disks or seats for the cans and a plurality of sets of seaming-rollers, of means for automatically feeding or delivering the cans or vessels onto the carrier and means for automatically discharging the cans or vessels from the carrier.

It also consists in the novel construction of parts and devices and in the novel combinations of parts and devices herein shown or described.

In the accompanying drawings, forming a part of this specification, Figure 1 is a plan view of a machine embodying my invention. Fig. 2 is a central vertical section. Fig. 3 is a detail side elevation of the mechanism for feeding and discharging the cans. Fig. 4 is a horizontal section on line 44 of Fig. 2. Fig. 5 is a detail horizontal section on line 55 of Fig. 2. Fig. 6 is a detail horizontal section

on line 66 of Fig. 2. Fig. 7 is a vertical section on line 77 of Fig. 6, and Figs. 8, 9, and 10 are detail elevations of the seaming-rollers.

In the drawings like letters of reference indicate like parts in all the figures.

In said drawings, A represents the frame of the machine. B is a continuously-moving carrier, preferably a rotary turret or wheel. The continuously-moving carrier B has a can-receiving plate or table B', furnished with a series of can-seats or chuck-disks b, having registering pins or devices b' for registering the cans with the opposing can chucking or clamping disks b², which are likewise mounted on the carrier above the seats or chuck-disks b, so as to clamp the can between them.

D D are a plurality of rotatable seaming-heads mounted on the carrier B and each provided with a set of double-seaming rollers or tools d d², each journaled in an adjustable block D', carried by a radially-movable tool holder or slide D², which is reciprocated in the seaming-head D by means of the cams f on the vertically-movable slide F, with which each seaming-head D is provided for the purpose of moving the seaming-rollers in and out successively, or one after another.

The cam-slides F are moved up and down in respect to the seaming-heads D as required to force the seaming rollers or tools against the work as the carrier B rotates continuously by means of a stationary cam F' on the frame of the machine operating through the levers F², which are pivoted to the carrier at F³ and engage grooves of collars F⁴.

The seaming-heads D are rotated in respect to the cans X, clamped between the chuck-disks b b², by means of spur-gears d³ on the shaft d⁴ of the seaming-heads, which engage a gear C, which may be stationary, but is preferably rotated in the opposite direction to the carrier B through the worm-gear C' and worm C². The carrier B is rotated by means of a worm-gear B² and worm B³.

To clamp or chuck the cans between the chuck-disks b b², one of these chuck-disks, preferably the lower one, is given a reciprocating movement. This is preferably done by means of a stationary cam B⁴ on the frame

of the machine engaging a bent lever B^5 , pivoted to the carrier and connected to the spindle of the chuck-disk b .

The chuck-disk or can-seat b has a rubber 5 or elastic pad b^3 thereon, and the upper chuck-disk b^2 preferably has a ball-bearing connection with the rotary seaming-head D to minimize the tendency of the rotary seaming-head to rotate the can. I prefer to rotate the seaming-heads, in which the seaming-tools are mounted, rather than the can chucking or clamping disks b b^2 , as I thus keep the cans from rotating and obviate any tendency to cause the liquid contents thereof to be thrown 15 out by centrifugal action.

The cans are automatically fed or delivered onto the can-seats or chuck-disks b of the continuously-moving carrier B from the can-carrier belt K by a movable feeder H, having a 20 series of can-pusher arms h , which engage the cans and move them along a curved guideway H' onto the flat plate, table, or ring B' of the carrier B and against the registering devices or pins b' of the can-seats. The 25 feeder H is preferably given a rotary movement in coöperation with the continuously-rotating carrier by means of operating-arms h' on the feeder, which engage pins or projections b^4 on the carrier B, or any other suitable gearing may be employed for connecting the feeder with the carrier. At the time the 30 cans are moved onto the carrier B and disk b the disk b is flush with the can-receiving plate B' of the carrier, as is also the case at 35 the time the cans are discharged from the carrier. The cans are automatically discharged from the carrier B as it rotates continuously by means of a can-discharging arm M, which 40 projects in the path of the cans and operates in conjunction with the guide M' to deliver the cans upon the can-discharging belt or conveyer N. The can-feed conveyer or belt K travels upon a pulley K' , and a plate H^2 , flush with the conveyer-belt K and carrier B, supports the cans as they are moved 45 by the feeder H from the conveyer K to the carrier B. A similar plate N' , flush with the conveyer N and carrier B, bridges the space between the carrier and said belt or conveyer N. The conveyer N travels upon a 50 suitable pulley N^2 .

The operation is as follows: The cans X on the feed-conveyer K are continuously crowded into the guide H' at the end of said conveyer, so that one of the cans is always in 55 position to be engaged by one of the feeder-arms h as the feeder H rotates, and thus be moved by the feeder-arm onto the carrier B and against the registering pins or devices b' of the can-seat or chuck-disk b . As the 60 carrier B continues its rotation the chuck-disk b is raised by operation of the stationary cam B^4 and connecting bent lever B^5 until the can is firmly clamped or chucked between the chuck-disks b b^2 , the seaming rollers or tools d d' d^2 being at this time retracted. As 65 the carrier B continues its rotation the cam-

slide F is reciprocated in respect to the rotating seaming-head D, and thus forces the first double-seaming roller d against the seam-flange of the can head or cover and curls it over the seaming-flange of the can-body, and as the downward movement of the cam-slide F continues the second and third seaming-rollers d' d^2 are brought successively into 75 operation, and the double seam thus completed, when the further reciprocating movement of the cam-slide withdraws all the seaming rollers or tools from contact with the can. As the rotation of the carrier B 80 continues the chuck-disk b is again brought flush with the can-receiving plate B' of the carrier and the can automatically discharged therefrom by the discharge device M. As the carrier is provided with a plurality or 85 series of can clamping or chucking disks b b^2 and with a plurality of seaming heads and sets of double-seaming rollers, a number of cans are thus being operated upon simultaneously as the carrier rotates continuously, 90 and the work is thus performed automatically and rapidly and cheaply.

I claim—

1. In a double-seaming machine, the combination with a continuously-moving can-carrier, of a plurality of pairs of can-clamping disks or chucks mounted thereon, a plurality of sets of double-seaming rollers mounted on the carrier, means for successively actuating the double-seaming rollers of each set in 95 respect to each other, and a feeder for automatically delivering the cans upon the continuously-moving carrier, substantially as specified.

2. The combination with a continuously-running carrier having a plurality of pairs of clamping disks or chucks mounted thereon, of a plurality of independently-rotating seaming-heads mounted on the carrier, and provided each with movable seaming rollers or 100 tools, substantially as specified.

3. The combination with a continuously-running carrier having a plurality of pairs of can-clamping disks or chucks mounted thereon, of a plurality of independently-rotating seaming-heads mounted on the carrier, and provided each with movable seaming rollers or tools, and a feeder for automatically delivering the cans upon the carrier, substantially as specified.

4. The combination with a carrier having a plurality of can-seats furnished with registering pins or devices for the cans, a plurality of opposing clamping disks or chucks, a plurality of rotating seaming-heads furnished 115 each with a set of movable seaming rollers or tools, a can-conveyer, and a feeder for delivering the cans from the conveyer to the carrier, substantially as specified.

5. The combination with a carrier having 120 a plurality of pairs of can-clamping disks or chucks mounted thereon, of a plurality of rotating seaming-heads mounted on the carrier and provided each with movable seam-

ing rollers or tools, and a cam-slide furnished with cams for successively operating the seaming rollers or tools, substantially as specified.

5 6. The combination with a carrier having a series of movable can-seats or chuck-disks, a stationary cam and connecting-levers for operating said can-seats or chuck-disks as the carrier rotates, a plurality of opposing can clamping or chuck disks, a plurality of seaming-heads having each a set of seaming-rollers, cam-slides for operating the seaming-rollers, and a stationary cam and connecting-levers for operating the cam-slides, substantially as specified.

10 7. The combination with a carrier having a series of movable can-seats or chuck-disks, a stationary cam and connecting-levers for operating said can-seats or chuck-disks as the carrier rotates, a plurality of opposing can clamping or chuck disks, a plurality of seaming-heads having each a set of seaming-rollers and a cam-slide for operating the seaming-rollers, a stationary cam and connecting-levers for operating the cam-slides, and a feeder for automatically delivering the cans to the carrier, substantially as specified.

15 8. The combination with a carrier having a series of movable can-seats or chuck-disks, a stationary cam and connecting-levers for operating said can-seats or chuck-disks as the carrier rotates, a plurality of opposing can clamping or chuck disks, a plurality of seaming-heads having each a set of seaming-rollers and a cam-slide for operating the seaming-rollers, a stationary cam and connecting-levers for operating the cam-slides, a feeder for automatically delivering the cans to the carrier, and a discharge device for automatically discharging the cans from the carrier, substantially as specified.

20 9. The combination with a rotating carrier having a series of can-clamping chucks or disks mounted thereon, a series of rotating seaming-heads having each a set of seaming-rollers and a slide for operating the seaming-rollers, and a stationary cam for operating said slides, substantially as specified.

25 10. The combination with a continuously-moving carrier having a plurality of can-seats thereon, of a plurality of opposing can-clamping disks, and a plurality of independently-rotating seaming-heads on the carriers furnished each with a set of movable seaming-rollers, substantially as specified.

30 11. The combination with a continuously-moving carrier having a plurality of can-seats thereon, of a plurality of opposing can-clamping disks, a plurality of rotating seaming-heads furnished with a set of movable seaming-rollers, and a plurality of movable slides for operating the seaming-rollers, substantially as specified.

35 12. The combination with a continuously-moving carrier having a plurality of can-seats thereon, of a plurality of opposing can-clamping disks, a plurality of rotating seaming-

heads furnished with a set of movable seaming-rollers, a plurality of movable slides for operating the seaming-rollers, and a stationary cam for operating said slides, substantially as specified.

40 13. The combination with a continuously-moving carrier having a plurality of can-seats thereon, of a plurality of opposing can-clamping disks, a plurality of rotating seaming-heads furnished with a set of movable seaming-rollers, a plurality of movable slides for operating the seaming-rollers, a stationary cam for operating said slides, and a stationary cam for reciprocating the can-seats to clamp or chuck the cans, substantially as specified.

45 14. The combination with a carrier having a plurality of movable can-clamping disks thereon, a plurality of opposing can-clamping disks, a stationary cam for operating said movable can-clamping disks as the carrier rotates, a plurality of sets of seaming-rollers and means for operating the same, a can-conveyer belt, and a feeder for automatically delivering the cans from the conveyer to the carrier, substantially as specified.

50 15. The combination with a continuously-running carrier having a plurality of movable can-clamping disks thereon, a plurality of opposing can-clamping disks, a stationary cam for operating said movable can-clamping disks as the carrier rotates, a plurality of independently-rotating seaming-heads on the carrier having each a set of seaming-rollers and means for operating the same, a can-conveyer belt, a feeder for automatically delivering the cans from the conveyer to the carrier, and a can-discharging device, substantially as specified.

55 16. The combination with a continuously-moving carrier having a plurality of can-clamping disks or chucks thereon, and provided with a plurality of independently-rotating seaming-heads on the carrier having each a set of seaming-tools, of means for automatically feeding or delivering the cans upon the carrier, substantially as specified.

60 17. The combination with a continuously-moving carrier having a plurality of can-clamping disks or chucks thereon, and provided with a plurality of independently-rotating seaming-heads on the carrier having each a set of seaming-tools, of means for automatically feeding or delivering the cans upon the carrier, and means for automatically discharging the cans from the carrier, substantially as specified.

65 18. The combination with a continuously-moving carrier provided with means for clamping or chucking a series of cans thereon, a plurality of seaming-heads on the carrier having each a set of seaming-rollers mounted on the carrier, means for rotating the seaming-tools and cans in respect to each other, and means for automatically feeding the cans upon the carrier, substantially as specified.

19. The combination with a continuously-moving carrier provided with means for clamping or chucking a series of cans thereon, a plurality of seaming-heads on the carrier having each a set of seaming-rollers mounted on the carrier, means for rotating the seaming-tools and cans in respect to each other, means for automatically feeding the

cans upon the carrier, and means for automatically discharging the cans from the carrier, substantially as specified.

JOHN G. HODGSON.
